UNITED STATES PATENT OFFICE.

CARL MILLER, OF SHENANDOAH, PENNSYLVANIA.

SAFETY-POCKET FOR TROUSERS.

1,118,789.

Specification of Letters Patent.

Patented Nov. 24, 1914.

Application filed December 24, 1913. Serial No. 808,589.

To all whom it may concern:

Be it known that I, CARL MILLER, a citizen of the United States, and a resident of Shenandoah, in the county of Schuylkill, 5 and State of Pennsylvania, have invented a new and Improved Safety-Pocket for Trousers, of which the following is a full, clear, and exact description.

This invention relates to garments and 10 has particular reference to the provision of a novel pocket construction adapted especially for men's trousers.

Among the objects of the invention is to provide hip pockets for trousers, the openings of which are practically invisible, making a garment of neat appearance.

Another object of the invention is to employ the pocket closure flap as a keeper for the belt and to provide the upper edge 20 of said flap with fastening devices securing it in place over said belt.

The foregoing and other objects of the invention will hereinafter be more fully described and claimed and illustrated in the 25 drawings forming a part of this specification in which like characters of reference will indicate corresponding parts in both the views, and in which—

Figure 1 is an elevation of a portion of 30 the upper rear part of a pair of trousers provided with my improvements; and Fig. 2 is a sectional detail on the line 2—2 of Fig. 1.

The several parts of the device may be 35 made of any suitable materials, and the relative sizes and proportions, as well as the general design of the mechanism, may be varied to a considerable extent without departing from the spirit of the invention 40 hereinafter more fully set forth and specifically claimed.

Referring more particularly to the drawings for a detail description of the construction, I show at 10 the rear or seat portion of a pair of trousers of any approved design, the same being provided with a pair of hip pockets 11. The main pocket as usual depends within the portion 10. Instead, however, of having an open or unprotected mouth or flap for the upper part 15 of the pocket, I provide a flap 12 stitched neatly along its lower edge at 13 to the outer edge of what would ordinarily be the

mouth of the pocket, as indicated at 14, Fig. 2. Said flap may have an inner lining 55 or facing 12' corresponding to the facing 11' of the pocket, if desired.

The trousers are shown provided with a waistband 15 having a facing 15', both of the waistband parts being stitched at 16 to 60 the upper edge of the main part of the fabric. Any suitable number or location of keepers 17 may be provided to carry a belt 18.

In the closed position, as shown at the 65 left side of Fig. 1, the upper edge 12^a of the flap is secured along the upper edge of the waistband by any suitable temporary fasteners such as snap buttons 19 and 20, leaving the outer face of the pocket and 70 its flap perfectly smooth and rendering the pocket not only invisible but incapable of access by a stranger without attracting the wearer's attention. Said flap also covers the belt adjacent the pocket and might in 75 some instances take the place of the usual belt keepers 17. Proper access to the pocket may, of course, be had by unfastening the upper edge of the flap, the flap dropping, as shown in the right portion of Fig. 1 and 80 in dotted lines in Fig. 2, and thereafter the flap may be closed and secured as above described. From my practical experience I have demonstrated that this improvement 85 may be easily incorporated in a pair of trousers and adds little expense thereto.

Having thus described my invention, I claim as new and desire to secure by Letters Patent:—

1. The herein described hip pocket construction for men's trousers, the same comprising the combination with the main fabric having a waistband, of a pocket construction having an opening below the waistband and including a flap stitched 95 along the upper outer edge of the pocket proper adjacent the lower edge of the waistband and movable upwardly into closing position, and fastening devices secured to the upper edge thereof adjacent the 100 upper edge of the waistband.

2. The combination with a pair of trousers and a belt carried thereby, of a safety pocket including a flap secured permanently along the edge of the pocket below 105 and parallel to the lower edge of the belt,

and fastening devices for securing the upper name to this specification in the presence
edge of the flap removably to the upper of two subscribing witnesses.
edge of the trousers parallel to and above
the upper edge of the belt, said flap con-
stituting a safety closure for the pocket and Witnesses:
5 constituting a keeper or guard for the belt. LEON FRIEBAND,
In testimony whereof I have signed my Z. F. LYNKIEWICZ.

Copies of this patent may be obtained for five cents each, by addressing the "Commissioner of Patents,
